ADDING MACHINE WITH INDICATING AND TENS TRANSFER MECHANISMS

Nils Evert Johan Ståhl, Stockholm, and Oscar Uno Larsson, Malarhojden, Sweden

Application January 4, 1952, Serial No. 265,012

4 Claims. (Cl. 235—60.31)

This invention refers to an adding machine with indicating and tens transfer mechanism, and the chief object of the invention is to provide such a machine which requires a minimum of space and thus can be used to advantage for instance in a portable ticket printing apparatus or the like, in which the space required by the adding machine as well as its weight are of essential importance. A further object of the invention is to provide an easily operated adding machine, which by printing or like indication is able to show the single figures or amounts entered as well as the total thereof, the latter indication being the result of an operation, which is not identical with the operation serving to enter the figures in the machine, and this latter operation is preferably effected by means of a key.

The invention refers to the type of adding machines known per se, which has arched amount setting members actuating, when angularly displaced about their centre, radially displaceable teeth a varying number of which is caused to displace against the centre of motion of the amount setting members when the latter are turned into the different setting positions, the actuated teeth being intended to co-operate with counting wheels, which are caused to accumulate the figure or amount determined by the number of teeth actuated. The present application is a continuation-in-part of application Serial No. 83,322, filed March 25, 1949, and now abandoned.

The invention will be described in detail in the following text, reference being had therein to the accompanying diagrammatic drawings, whereby the features of the invention will become evident. It must be pointed out, however, that for elucidating purposes the drawings show a machine with portions broken away to facilitate the understanding of its functioning and with gear wheel structures abnormally extended in the axial direction, which of course is not found in a practical embodiment. The machine illustrated in the drawings is primarily intended for use in a portable ticket printing apparatus, thus presenting an embodiment of the invention which within certain limits may be modified to suit another purpose.

In the drawings:

Fig. 1 is a perspective view of the adding machine, which is normally fitted with five amount setting members with pertaining radially displaceable teeth, four of which however are broken away for revealing the accumulating and indicating mechanism of the machine, the latter in turn being partly broken away to facilitate the tracing of the machine operations.

Fig. 2 shows a portion of the machine corresponding to the remote part of Fig. 1 at a stage when the set amount is being entered into the accumulator of the machine.

Fig. 3 also is a partial view of Fig. 1, but shows a stage when the accumulator is performing a tens transfer actuated by a rigid tooth in the frame of the machine.

Fig. 4 is a partial view of the operative parts of the machine while transmitting the positions of the counting wheels to the indicating mechanism, which operation may also be denominated a reading off or an "emptying."

Generally speaking, the machine according to the invention consists of three main parts, viz, for the first thing a set of amount setting members each similar to the single setting member 1 illustrated in Fig. 1, although in the machine herein described five such members are required, for the second a rotatable frame structure 2 with pertaining driving mechanism 3, said frame construction accommodating the counting wheels accumulating the set amounts, as well as a tens transfer mechanism connecting in pairs the accumulating wheels for the different

decades, and for the third an indicating mechanism 4 which is normally actuated directly from the different amount setting members 1 for adjustment into positions corresponding to the positions of the amount setting members 1 when entering a certain amount or figure into the machine, but which is also capable to show the total of the amounts or figures entered into the machine as will be described later on in this text.

The outstanding and chief feature of the machine is the rotating frame 2, which carries the counting wheels and tens transfer means. The other parts of the machine may be varied by the expert within wide limits and are known for essential part from machines of similar kind, although in connection with the rotating frame they constitute a new and expedient combination.

The frame 2 is rotatable about shaft pivots 5 journalled in a suitable way in a machine frame, which is not shown in the drawing, and the rotation of the frame is effected by means for an operating lever 6 which is swingably journalled in the machine frame and via a toothed sector 7 engages a toothed ring 8 mounted on a sleeve 9 which is rotatable coaxially with the shaft pivots of the frame 2, said sleeve 9 further carrying a toothed rim 10 with set teeth arranged to co-operate with a spring-actuated catch 11 provided at one end of the frame 2, so that the frame 2 is caused to rotate in one direction only at each actuation of the operating lever. In the machine shown the frame 2 is thus caused to rotate anti-clockwise in the direction indicated by the arrow 12, when the operating lever is moved forwards in the direction indicated by the arrow 13, whereas the frame 2 remains in its position, retained by special brake means not shown in the drawing when the operating lever 6 is restored to its initial position. The driving mechanism 3 for the frame 2 is so adapted, that the frame is caused to accomplish exactly one whole revolution each time the operating lever 6 is swung forwards by a distance corresponding to or exceeding the centre angle of the toothed sector 7. The operating lever 6 is suitably restored to its initial position by means of a spring (not shown in the drawing). The driving mechanism illustrated in the drawing is chosen wholly arbitrarily and may be replaced with any other driving device, by means of which the frame 2 can be intermittently rotated by one revolution about its axis of rotation to allow the adding function of the machine.

As already mentioned, the frame 2 represents the heart of the machine, and it includes, mounted on shafts 14 and 15 respectively which are eccentric relative the axis of rotation of the frame proper, a series of coaxial counting or accumulating wheels 20, 21, 22, 23 and 24 journalled so as to be freely rotatable on the shaft 14 but prevented from moving axially in the frame 2, which wheels are representing the different decades in the adding machine and are all of them provided with ten teeth, and further a series of tens transfer members 25, 26, 27 and 28, which are journalled on the shaft 15 so as to be freely rotatable but prevented from moving axially in the frame 2 and which are intended for transmitting the tens from the counting wheels of a lower decade to the counting wheels of the adjacent higher decade. Each counting wheel 20—23 is equipped with a hub sleeve 29 carrying at a certain axial distance from the teeth of the respective counting wheel a radially projecting tooth 30. Said tooth 30 assumes such an angular position relative the teeth of the counting wheel that it will enter a clearing between two counting wheel teeth, and it serves to actuate the adjacent tens transfer member in a manner to be described later on in the text. The remote counting wheel 24 of the machine shown is without tooth 30, since said counting wheel represents the highest decade of the machine. However, there is nothing to prevent that for the sake of uniformity also this wheel is equipped in the same manner as the other counting wheels.

Each tens transfer member consists of a hub sleeve, at one end of which (the front end in the drawing) are mounted two gear wheels 35, 36 adjacent one another, the other end of the sleeve carrying a third gear wheel 37. Each gear wheel 35, 36 and 37 respectively on the tens transfer members 25—28 is provided with four teeth only, which are at right angles to each other, but the wheels are so large that the distance between the teeth of each

wheel represents three pitches. In other words it may be said that the gear wheels 35, 36 and 37 represent twelve-toothed wheels having some teeth removed and only every third tooth left. The tooth module of said gear wheels 35, 36 and 37 at each tens transfer member is the same as that of the counting wheels, the tooth 30 of the counting wheels also being made according to this module.

In the machine shown in the drawing, the tooth 30 co-operates during the tens transfer with one of the teeth on the gear wheel 35, whereby a rotary movement corresponding to one pitch is imparted to the respective tens transfer member. As a consequence the next gear wheel 36 on the tens transfer member, the teeth of which are angularly displaced by an angle corresponding to two pitches relative the teeth of the first-mentioned gear wheel 35 in the direction of rotation of the tens transfer members, is brought into a preliminary tens transferring position, although the ten is not yet transferred to the counting wheel of the next decade. The remote gear wheel 37 on the tens transfer member, the teeth of which serve to actuate the counting wheel of the next decade and are angularly displaced by one pitch relative the teeth of the first-mentioned gear wheel 35 in the direction of motion of the tens transfer member, is simultaneously caused to assume a position, in which it is momentarily ready to impart a movement of one pitch to the counting wheel of the next decade when a rotary movement of further two pitches is imparted to the tens transfer member as a unit, to the effect that the tens transfer member assumes a new initial position for the next transfer.

This last-mentioned rotary movement corresponding to two pitches is imparted to the tens transfer member by a tooth 38 stationary mounted in the machine frame and arranged to co-operate with the gear wheel 36 during the rotation of the frame 2 and spaced by such a distance from the axis of rotation of the frame 2, that only when the tens transfer member with its gear wheel 36 assumes its preliminary position it will contact that tooth of the gear wheel 36 which has been swung out from the axis of the frame 2 in the preliminary position. When the tens transfer member is still in the preliminary position and the tooth 30 has not yet actuated the gear wheel 35, the stationary tooth 38 thus does not actuate the tens transfer member because the teeth of the gear wheel 36 only tangent and do not project beyond the circle outside which the tooth 38 is operative. One stationary tooth 38 is arranged to co-operate with each tens transfer member 25, 26, 27 and 28 respectively, and the stationary teeth 38 for the different tens transfer members are angularly displaced relative one another about the axis of rotation of the frame 2 in such a way that the tens transfer member 25 intermediate the two lowest decades is first caused to perform its tens transferring movement and then the following tens transfer members 26, 27 and 28 in succession. Expressed in other words, this means that the stationary tooth 38 for the tens transfer member 25 is the first one of the stationary teeth to be set in function and to retard its tens transfer member, and that the stationary teeth of the following tens transfer members are successively angularly displaced relative the first-mentioned tooth in the direction of rotation of the frame.

Besides counting wheels and tens transfer members the frame 2 carries entering wheels 40 corresponding in number to the counting wheels and journaled to be freely rotatable on short shaft pivots 42 supported in lugs 41 on the frame 2, so that each of said entering wheels will permanently mesh with one counting wheel 20-24. These entering wheels 40 are only intended to facilitate the entering of the figures or amounts to be accumulated by the counting wheels.

As will be obvious from the foregoing text, the rotatable frame with the adding mechanism of the machine constitutes a normally completely free unit in the machine, which during an essential part of its path of motion is not in counting engagement with the other machine parts, and which may therefore be taken out of the machine for control and adjustment, if necessary. The figures or amounts to be accumulated by the counting wheels 20-24 of the different decades are entered into the accumulator and the individual counting wheels during the rotation of the frame 2. During a certain part of said rotation each entering wheel 40 is caused to co-operate with teeth 51-59 radially guided in the machine frame and arranged in groups in the path of motion of

each entering wheel, said teeth pointing towards the axis of rotation of the frame 2. In other words, each group of radially displaceable teeth 51-59 forms a fan around a portion of the periphery of the frame 2, and each tooth is provided with a laterally projecting pin 60 entering a guide slot 61 or a guide groove in the arc-shaped amount setting wheel 1, which is adjustable, by means of special guidings not shown in the drawing by rotation about a centre coinciding with the axis of rotation of the frame 2. The groove or slot 61 in each amount setting member 1 is divided into two angularly displaced portions 61' and 61'' of substantially the same arch length, said two portions having a common centre coinciding with the axis of rotation of the frame 2 but separate radii, so that the portion 61' is located nearer to the centre than the portion 61''.

The two portions are forming a continuous groove by the provision of a rather steep submergion 62 between the opposite ends of the two portions. Since the teeth 51-59 are radially displaceable only and their pins 60 co-operate with the slot or groove 61 in the amount setting member 1, the radial position of the teeth 51-59 will be determined by the fact whether the pins of the respective teeth are in engagement with the portion 61' or the portion 61'' of the slot or groove 61, and the submergion 62 between the slot portions will form the point where the radial displacement of each tooth takes place. If the pins 60 of all the teeth 51-59 are in engagement with the outer slot portion 61'' in the pertinent amount setting member 1, all teeth of this group are inoperative. On the other hand, if the pins 60 of some of the teeth, for instance those of the teeth 51 and 52, as shown in the drawing, are caused to enter the inner slot portion 61' due to the amount setting member being rotated a certain angle from its zero position, said teeth 51 and 52 will be situated in the path of motion of the entering wheel 40 so that the entering wheel will be rotated by the operative teeth a number of pitches corresponding to the number of operative teeth. (in the drawing the teeth 51 and 52) when the frame 2 is turned one revolution, and a corresponding rotary motion is imparted to the counting wheel 20, 21, 22, 23 or 24 corresponding to the entering wheel in question.

As mentioned already, one amount setting member 1 with pertaining group of radially displaceable teeth having the function recently described is provided for each one of the counting wheels 20-24 forming part of the portion of the machine, which shall be usable for accumulation. To increase the adding capacity of the machine, the frame 2 may of course be provided with a greater number of counting wheels with intermediate tens transfer members than what corresponds to the number of amount setting members 1, and in most cases this is even necessary, although it has not been shown in the drawing, amount setting members 1 then being arranged for the counting wheels of some of the first decades only. Thus it would be preferable in the machine shown in the drawing to provide amount setting members of the type recently described for the counting wheels 20, 21 and 22 only, while the counting wheels 23 and 24 should serve merely as tens accumulation members in succession as has been described already. However, this means no change in design of the counting wheels 23 and 24, and they shall still co-operate with entering wheels 40, which, however, are not performing any entering function as far as the latter counting wheels are concerned. The reason why, despite this, the entering wheels should be provided will appear from the following text and is concerned with the zeroizing of the accumulator. Thus, the amount setting member 1 shown in the drawing is placed so as to co-operate with the counting wheel 24 of the highest decade only, because this facilitates the revealment of the machine mechanism.

Each amount setting member 1 is made in the form of an arched plate and is rigidly connected at its periphery to a corrugated operating body 65, which extends peripherically along the amount setting member 1 over a length at least corresponding to the rotability of the latter. On its outer side the operating body 65 carries figure marks 66 provided in wave troughs thereon, which are serving as supports for the fingers at the manual operation of the amount setting members. The operating body 65 co-operates with a rigid support edge 67 of the machine frame in such a manner that by placing a

finger in the wave trough of the operating body 65 marked with the figure to be entered into the machine and then turning the operating body and thus also the amount setting member until the finger placed in the wave trough comes to rest against the support edge 67, it is ensured that the corresponding number of teeth 51—59 is pushed in radially and will actuate the counting wheel of the corresponding decade at the rotation of the frame 2. In the drawing, by way of example, the wave trough carrying the Figure 2 has been moved down to the support edge 67 and the two teeth 51 and 52 have been brought into their operative position to co-operate with the counting wheel 24. To withdraw the operative teeth from their operative positions the setting member 1 is moved up (counterclockwise, Fig. 1) to zero position by a hand manipulation of the operating body 65. This action restores all of the operative teeth to inoperative positions in which they are retained by the portion 62' of the cam groove 61.

On its inner edge facing the centre of rotation, each amount setting member 1 is provided with an internal toothed 70, which is in permanent engagement with an operating gear 72 mounted on a stationary shaft 71, said gear 72 being freely rotatable on said shaft. Normally, each operating gear 72 is in mesh with an intermediate wheel 74 carried by an axially displaceable intermediate shaft 73. Each intermediate wheel 74 is connected with the common shaft 73 by a friction device 75, the operating gears 72 as well as the intermediate wheels 74 being axially non-displaceable relative their respective shafts.

The object of the friction device 75 will be explained later on in the text, and during the entering procedure the intermediate wheels 74 may be considered as freely rotatable about the shaft 73, although against some resistance. Each intermediate wheel 74 in turn is in mesh with a type gear wheel 76, 77, 78, 79 or 80, which is rigidly connected with one of the type wheels 81, 82, 83, 84 or 85 in the indicating mechanism 4 of the machine, said mechanism consisting of a printing device, not illustrated in detail, for printing receipts or tickets. The type gear wheel 76 is connected with the type wheel 81, the type gear wheel 77 with the type wheel 82 etc. so that the type gear wheel 80 is connected with type wheel 85 by means of telescopic shafts 86, corresponding in number to the type wheels, the tubular shaft 86', which connects the type gear wheel 80 with the type wheel 85, being the outermost one of all the telescopic shafts, as viewed in the radial direction. Thus, if the amount setting member for the counting wheel 20 is adjusted on a certain figure, the type wheel 81 will be correspondingly adjusted, by the intermediary of the type gear wheel 76, the same thing being the case for all decades. If now the driving mechanism of the frame 2 is connected in any arbitrary way with the printing mechanism co-operating with the type wheels 81—85, the apparatus can be caused to print a receipt or a ticket indicating the amount which has been entered into the counting wheels and set by means of the amount setting members 1.

It might appear from the foregoing, that the machine can be caused to accumulate the amounts entered, continuously indicating said amounts, and to add them together to a total, the size of which is represented by the positions of the counting wheels 20—24 located in the frame. Accordingly, it would be possible to read off the total of the entered amounts directly in the rotating frame 2 provided that the different counting wheels were equipped with figure marks, but this meets with certain inconveniences since the frame 2 is not stationary and, besides, the counting wheels are inconveniently positioned in the machine for being visually read off from the outside. Therefore, steps have been taken to allow a reading of the counting wheel positions via the indicating mechanism, i. e. the type wheel gear and the type wheels, to the effect that in the present case a receipt showing the total of the amounts entered into the machine is stamped out by the printing mechanism. In doing so, the accumulator must be "emptied out" into the set of type wheels, but it must be possible to reintroduce the amount from the latter to the accumulator for continued adding operation if desired, or it must otherwise be possible to zeroize both accumulator and type wheels after the "emptying" to allow a new series of adding

operations completely independent of those earlier effected.

The "emptying" takes place, when the frame 2 is in its position of rest, by means of a key 90 which is pushed in from the outside over a square end 91 on the shaft 14 carrying the counting wheels 20—24. With the key 90 the shaft 14 is turned one revolution in the direction opposite to that in which the counting wheels are moving during the accumulating operations, and the shaft 14 is axially displaceable against the action of a spring 92, the counting wheels 20—24 as already mentioned being axially non-displaceable in the frame 2. At the remote end of the shaft 14 is a radial pin 93, which normally engages a groove or recess 94 in the end portion of the frame 2, but when the shaft 14 is turned by means of the key 90, the pin 93 is moved out of the recess 94 so that an axial displacement of the shaft is effected. This axial displacement brings about the effect that during the rotation of the shaft rigid knobs 95 provided at the shaft 14 in a number corresponding to the number of counting wheels are caused to co-operate with an axially protruding lug 96 at each counting wheel 20—24 if the position of the counting wheel represents any other figure than zero, and the counting wheels are restored by the shaft to their zero-positions but not further, because the pin 93 then enters the recess 94 again, which allows the passing of the knobs 95 past the zero positions of the lugs 96. In order that the turning of the counting wheels shall not merely mean a zeroizing thereof when the shaft 14 is turned by means of the key 90, there is provided adjacent each type gear wheel 76—80 an axially displaceable but unturnable additional wheel 97, which is carried by the shaft 86 of the respective type gear wheel and is normally held at a certain axial distance from the type wheel by a spring 98, but is brought in engagement with the entering wheel 40 of the respective counting wheel if pressed against the pertaining gear wheel.

To prevent the amount setting members 1 from partaking in the movement and being turned at the emptying of the accumulator, the intermediate shaft 73 is besides arranged to be axially displaced in the direction to the right in the drawing, so that the intermediate wheels 74 at the intermediate shaft are released from the engagement with the respective operating gears 72 and will instead, like the entering wheels 40, engage the additional wheels 97 adjacent the different type gear wheels. The motions of the additional wheels 97 and the intermediate shaft 73 with its intermediate wheels 74 are co-ordinated by means of a lever and fork mechanism 99, which is actuated by an axial displacement to the right of the intermediate shaft 73. This axial displacement of the intermediate shaft is obtained mechanically at the co-operation of the key 90 with the shaft 14 thanks to a lever 100 which is swingably journaled in the machine frame and is actuated at its end 101 by a flange 90' on the key, said lever 100 being connected with the intermediate shaft 73. As soon as the key 90 is caused to co-operate with the counting wheel shaft 14, the intermediate shaft 73 and thanks to the lever and fork mechanism 99 also the additional wheels 97 are thus displaced so that the amount setting members are totally disengaged and the rotation of the counting wheels 20—24 will be transmitted to the respective type wheels 81—85. When the key is disengaged from the counting wheel shaft, the intermediate shaft as well as the additional wheels will return to their normal positions.

After the total amount entered into the machine has been stamped out or read off in any arbitrary way through the type wheels 81—85, the latter are zeroized by turning the intermediate shaft 73 with the same key, the key effecting an axial previously described so that the amount setting members are disengaged. If now the intermediate shaft 73 is turned by means of the key 90, the intermediate wheels 74 taken along with the intermediate shaft under friction will turn the additional wheels 97 on the shafts of the type gear wheels to the effect that the type wheels are restored to zero position, the amount recently accumulated by the same simultaneously being returned unchanged to the respective counting wheels 20—24 via the additional wheels 97 and the entering wheels 40. The "emptying" of the accumulator with subsequent re-entering thus described may be performed whenever desired for controlling purposes, and the machine will always add every new-entered fig-

ure or amount to the total of those already accumulated. In this connection it should be observed, that the machine must be equipped with one type gear wheel with pertaining type wheels for each counting wheel in the machine, and that also the intermediate shaft 73 must be provided with friction-loaded intermediate wheels corresponding in number to the counting wheels in order to allow the emptying operation, disregarded whether the counting wheels included in the machine are intended for co-operation with amount setting members during the entering operation or merely serve to accumulate tens.

When going to zeroize the machine for then performing a new adding completely independent of earlier adding operations, the mounting wheels are first "emptied" into the type wheels 81-85 by turning the counting wheel shaft 14 by means of the key 90, so that all counting wheels are zeroed as described earlier, and the key 90 is removed from the counting wheel shaft 14, the springs 98 between the type gear wheels 76-80 and the pertaining additional wheels 97 restoring the additional wheels to inoperative positions and simultaneously restoring, via the lever and fork mechanism 99, the intermediate shaft 73 with its intermediate wheels 74 to normal position, at which moment the counting wheels in the frame 2 are again entirely disengaged from the type wheel gear and the amount setting members. Instead of pressing the intermediate shaft 73 to the right in the drawing by means of the key 90 as earlier described for the zeroizing of the type wheels 81-85, there is depressed a spring-actuated push button 105, which actuates the lever 100 on the opposite side of its pivot axle 102, reckoned from the intermediate shaft 73, so that the intermediate shaft 73 is displaced axially to the left in the drawing, the intermediate wheels 74 being disengaged from the operating wheels 72 again but still maintaining their original engagement with the type gear wheels 76, 77, 78, 79 and 80 respectively by the latter having been given a larger width or axial length. During this movement of the intermediate shaft the lever and fork mechanism 99 remains inoperative and thus does not influence the additional wheels 97, for which reason the latter remain disengaged from the entering wheels 40. If now the intermediate shaft 73 is rotated by means of the key 90 while the push button 105 is all the time depressed, the type wheels 81-85 are zeroized without the figure values accumulated therein being returned to the counting wheels 20-24. The moment the pressure on the push button 105 ceases, its spring 106 restores the lever 101 and thus also the intermediate shaft 73 to the normal position, in which the intermediate wheels 74 again serve to transmit the motions of the amount setting members to the type gear wheels 76-80.

It may be considered suitable to provide a checking rule for the type gear wheels to assure that the type wheels always are in the correct position for printing the set amount. This checking rule may be shaped as a swingable doctor blade parallel with the type gear shafts and entering the opening between two adjacent teeth in each type gear wheel thereby preventing it from turning as soon as the printing operation starts but again releasing the teeth as soon as the printing operation has ended.

Of course the invention is not confined to the embodiment shown in the drawing but may be varied with regard to size and design as well as to the arrangement of the parts. In a simpler construction of the machine, it is thinkable to dispense with the entering wheels 40 and accordingly also the operating wheels 72, and of course the type wheels 81-85 must not necessarily be printing wheels in a ticket or receipt printing machine, but may be adapted for direct visual reading through a window or the like, or may combine both these modifications.

Having now described our invention, what we claim as new and desire to secure by Letters Patent is:

1. In apparatus of the class described, a rotatable frame, a shaft carried by said frame and having counting wheel gears of an accumulator journalled thereon, intermediate gears rotatably mounted on said frame and meshing with said counting wheel gears, settable teeth arranged in an arc concentric to the axis of said frame and settable to actuate said intermediate gears when said frame is rotated, printing wheel gears, one for each of said intermediate gears, said printing wheel gears being journalled on a fixed shaft spaced from said frame, means for temporarily meshing with said printing wheel gears

and means to zeroize said counting wheel gears and at the same time actuate said printing wheel gears to transmit thereto the values previously contained on said counting wheel gears.

5 2. In apparatus of the class described, a rotatable frame, a shaft carried by said frame and having counting wheel gears of an accumulator journalled thereon, intermediate gears rotatably mounted on said frame and meshing with said counting wheel gears, settable teeth arranged in an arc concentric to the axis of said frame and settable to actuate said intermediate gears when said frame is rotated, and transfer mechanism for said accumulator including a transfer stub carried by each counting wheel gear, hub members rotatably mounted on a second shaft carried by said frame, each of said hub members carrying a mutilated gear actuatable by a transfer stub of a lower order counting wheel gear for conditioning said member for a transfer movement, a second mutilated gear actuatable by a fixed tooth for effecting a transfer movement of said member at the rotation of said frame, and a third mutilated gear for actuating the next higher order counting wheel gear one step.

20 3. In apparatus of the class described, a rotatable frame, a shaft carried by said frame and displaced to one side of the axis of rotation of said frame, said shaft having counting wheel gears of an accumulator journalled thereon, intermediate gears carried by said frame and meshing with said counting wheel gears, settable teeth arranged in an arc concentric to the axis of said frame and settable to actuate said intermediate gears when said frame is rotated, and transfer mechanism for said accumulator including a transfer stub carried by each counting wheel gear, hub members rotatably mounted on a second shaft carried by said frame and located to the other side of the axis of said frame, each of said hub members carrying three mutilated gears, each gear having four teeth equispaced at three pitches, one of said mutilated gears being actuatable by a transfer stub of a lower order counting wheel gear for conditioning said member for a transfer movement, the second of said mutilated gears being actuatable by a fixed tooth for effecting a transfer movement of said member at the rotation of said frame and the driving engagement of a tooth of said third mutilated gear with the next higher order counting wheel gear to effect the tens transfer.

25 4. In apparatus of the class described, a rotatable frame, a shaft carried by said frame and having counting wheel gears of an accumulator journalled thereon, intermediate gears rotatably mounted on said frame and meshing with said counting wheel gears, settable teeth arranged in an arc concentric to the axis of said frame and settable radially to actuate said intermediate gears when said frame is rotated, printing wheel gears, one for each of said intermediate gears, said printing wheel gears being journalled on a fixed shaft spaced from said frame, means for temporarily meshing said intermediate gears with said printing wheel gears, means to zeroize said counting wheel gears and at the same time actuate said printing wheel gears to transmit thereto the values previously contained on said counting wheel gears, and transfer mechanism for said accumulator including a transfer stub carried by each counting wheel gear, hub members rotatably mounted on a second shaft carried by said frame, each of said hub members carrying a mutilated gear actuatable by a transfer stub of a lower order counting wheel gear for conditioning said member for a transfer movement, a second mutilated gear actuatable by a fixed tooth for effecting a transfer movement of said member at the rotation of said frame, and a third mutilated gear for actuating the next higher order counting wheel gear one step.
